AUTOMATIC LEVEL TRANSIT OR THE LIKE

J. Peter E. Kooi, Succcasunna, and Allister L. Baker,
Denville, N.J., assignors to Keuffel & Esser Company,
Morristown, N.J.

Filed Aug. 22, 1973, Ser. No. 390,458

Term of patent 14 years

Int. Cl. D10—04

U.S. Cl. D10—66

FIG. 1

FIG. 2

FIG. 3

FIG. 4

FIG. 5

FIG. 1 is a left side elevational view of an automatic level transit or the like showing our new design;

FIG. 2 is a rear elevational view thereof;

FIG. 3 is a top plan view thereof;

FIG. 4 is a right side elevational view thereof; and

FIG. 5 is a front elevational view thereof.

We claim:

The ornamental design for an automatic level transit or the like, as shown and described.
